LATCHING DEVICE

John B. O'Connor, Aurora, Ill., assignor to Lyon Metal Products, Incorporated, Aurora, Ill., a corporation of Illinois

Original application January 12, 1939, Serial No. 250,568. Divided and this application February 24, 1941, Serial No. 380,245

1 Claim. (Cl. 292—340)

This invention relates to keepers for latching devices for locker doors and the like. The present invention is a division of my application Serial No. 250,568, filed January 12, 1939, issued as Patent No. 2,242,958.

Among the objects of the present invention are to provide an improved keeper having opposed shoulders adapted to cooperate with latching members and arranged so that the keeper will pass freely in one direction by the latching members, but will be locked with respect to the latching members on retrograde relative movement between the keeper and the latching members; to provide a simple type of keeper preferably formed of sheet metal, and provided with locking shoulders formed also of sheet metal and assembled to the keeper proper by a very simple assembling operation; to provide a keeper formed of a strip of sheet metal bent to substantially U-shaped formation, providing a free leg adapted to receive a sheet metal clip which, when united thereto, forms a keeper shoulder or locking member; to provide an improved type of keeper formed of sheet metal bent substantially U-shaped so as to receive a resilient abutment in the hollow of the U-shaped structure, and whereby one of the legs of the U-shaped structure is adapted to receive a clip to provide a locking shoulder for the keeper; to provide a keeper formed of sheet metal providing a very rugged, simple, and economical locking device for a latching mechanism of a locker or the like; to provide these and other objects of the invention as will be apparent from a perusal of the following specification when taken in connection with the accompanying drawing, wherein—

Figure 1 is a perspective view of a locker construction;

Figure 2 is a perspective view of a portion of the edge of the locker door shown in Figure 1, portions thereof being broken away to show the internal construction;

Figure 3 is a detail, sectional view of the latching construction taken on the line 3—3 of Figure 2;

Figure 4 is a sectional detail view the same as Figure 3, but showing the parts in an alternative position;

Figure 5 is a detail, sectional view taken on the line 5—5 of Figure 3;

Figure 6 is a view the same as Figure 5, but showing the position of the parts as the latch begins to engage the keeper; and

Figure 7 is a detail perspective view of the

keeper forming the subject matter of the present invention.

Figure 8 is a view taken on line 8—8 of Figure 7.

The keeper forming the subject matter of this invention is adapted to cooperate with latching members carried by a door of a locker, the keeper being formed with opposed shoulders, and the keeper being arranged so that relative movement between the latching members and the keeper in one direction will permit the free passage of a latching mechanism past the keeper shoulders, but which shoulders on relative retrograde movement will prevent unlocking of the latching members from the keeper. In fact, the shoulders are arranged to provide in connection with the keeper a positive locking action.

Referring to the drawing, I have illustrated the invention as applied to a locker. It is evident, however, that the device has other adaptations and other applications. In the form of lockers illustrated in general by the reference number 10, the door 12 is mounted in a door frame 14. The door frame 14 mounts a pair of keeper members indicated by the reference numeral 16 (see Figures 1, 5, and 6). Each keeper member comprises a generally elongated strip or blank of sheet metal bent to substantially U-shape and having an attaching flange 18 integrally formed with one of the legs of the keeper. This flange 18 is welded to the inner face of the door frame 14 and is arranged so that the generally U-shaped portion extends into the door opening. The U-shaped portion comprises a rearwardly extending arm 20, a laterally extending portion 22 at the rearward extremity of the arm 20, and a second leg 24 projected forwardly at the door opening and provided with a free edge. The leg 24 is provided along its forward vertical edge with a locking shoulder adapted to engage the latching member hereinafter recited. This locking shoulder in the present invention is formed very simply, preferably it is formed as a sheet metal clip or cap 26 of generally U-shaped cross-section and is secured in a position overlying the free edge as shown in the drawing, in which position it is secured thereto by indenting as at 28, or by riveting, or welding. Preferably it is secured by indenting. This clip as shown particularly in Figures 3 and 4 is relatively long and corresponds substantially with the entire width of the leg 24. The depth of the keeper is, as shown, many times the depth of the cap 26. The free ends of the clip provide rearwardly

facing locking shoulders 27 for cooperation with the latching means.

The legs of the keeper are preferably reinforced as at 29 by means of bumped out portions, thereby giving the U-shaped tongue or keeper considerable rigidity. In addition, the two legs of the keeper substantially at the junction of the wall 22 are provided with registering openings 29' through which projecting tongues of a resilient buffer project whereby to hold the buffer in assembled position to the keeper, and thus providing a positively supported cushion to relieve the impact of the door.

The door 12 is mounted upon hinges 32 and in the illustration shown is formed of sheet material flanged adjacent its edges to form a generally reversely extending portion providing a box-like enclosure. More particularly, the upwardly extending free edge of the door (as clearly shown in Figures 2, 5, and 6) is first flanged rearwardly as at 34 and then laterally as at 36 in a plane parallel to the plane of the door, but spaced rearwardly therefrom. Within the U-shaped enclosure thus provided is mounted a vertically extending channel member 38 having a base wall 40 and opposed parallel side walls 42 and 44, respectively. The channel member 38, while engaged snugly by the flanges 34 and 36, is nevertheless supported thereby for vertical reciprocation. Any suitable means (not shown) may be employed for retaining the channel member in the position shown for free, adjustable reciprocation within predetermined limits. To this end there may be employed a detent or pin in one of the members engaging in a vertically extending slot in the other member.

Vertical movement of the channel member is controllable by means of a handle construction 46 comprising an outer handle element 48 which is secured to the outer surface of the door by fastening means (not shown in detail) and by an inner, relatively movable handle construction 50. The inner handle has rearwardly extending tabs or flanges 52 which project through a pair of elongated slots 54 in the front portion of the door and are fastened directly to the rear wall 40 of the channel member by fastening means 56. An angle member 58 forms a housing enclosing the elongated slots 54 on their inner sides so that instruments cannot be inserted through the slot to tamper with the latching mechanism.

In order that the angle member 58 will enclose and house the inner faces of the elongated apertures 54, it is secured to the channel member and is preferably of relatively considerable length so that it resides opposite the apertures 54 regardless of the vertical adjustment of the bar. While not shown in detail, the angle member 58 has end walls providing a substantially complete enclosure, and may be provided with flanges for welding directly to the rear wall of the channel in accordance with the structure more fully disclosed in my Patent No. 2,195,223 issued March 26, 1940, of which the application, Serial No. 250,568, filed January 12, 1939, issued as Patent No. 2,242,958, for Latching device, is a continuation in part.

It will be apparent from the foregoing that by grasping the inner handle 50 and moving it upwardly relative to the outer handle 48, the channel member will be shifted vertically a predetermined distance. A downwardly projecting lug 60 on the inner handle projects through a corresponding aperture in the outer handle 48

(see Figure 2) and is apertured in its lower extremity as at 62 to receive a locking device.

In order to enable the door to reach closed position (as shown in Figures 3, 4, and 5), the rearward door flange 36, as well as the flange 42 of the channel member 38, are apertured as at 64 and 66, respectively, opposite each forwardly extending keeper portion. The aperture 64 may be, and is in the embodiment shown, 5 preferably smaller in vertical extent since the aperture 66 must permit entry of the keeper in spite of the varying vertical adjustment of the channel.

On the interior surface of the channel wall 15 42, there is mounted a latching construction 20 comprising an elongated length of wire formed (as clearly shown in Figure 2) to provide parallel, spaced, vertically extending resilient legs 68 provided with rectangularly shaped lateral 25 projections intermediate of their length and extending in relatively inclined planes. These 30 projections (as shown more clearly in Figure 2) comprise parallel arms 70 projecting laterally from each of the vertically extending legs and joined by a transversely extending keeper engaging 35 portion or latch 72. It is important to note that each of these projecting portions 70 is inclined with respect to the plane of the vertical legs 68 and that they converge together as they progress from said plane. The legs 68 are joined together adjacent their lower ends by a lateral arm 74 and at their upper ends by a lateral arm 76 which latter may be joined or which may merely comprise two ends of the wire arranged in abutment as shown in the Figure 8 of Patent No. 2,242,958.

The elongated member is mounted upon and supported by a mounting means (shown more clearly in Figure 2) and comprising a main, 40 upwardly extending wall 78 apertured as at 80 to correspond with the aperture 66 in the wall of the channel member and having lateral, short, projecting side flanges 82. It should be noted that the flanges 82 are spaced just sufficiently to 45 oppositely engage the vertically extending arms 68 of the elongated latching member to retain them in position. The upper and lower transversely extending arms 74 and 76 of the latch member are engaged by curved, recessed flanges 50 84 adjacent the upper and lower ends of the mounting frame.

It should be noted particularly that the curved, recessed flanges 84 provide recesses on the rearward face of the supporting and mounting frame 55 so that the elongated arms 74 and 76 are engaged behind the mounting member while the vertically extending arms 68 are engaged adjacent the forward side thereof, thereby firmly and rigidly interconnecting the latching member and its supporting frame. Curved arm engaging flanges 84 are extended oppositely as at 86 to provide flat attachment flanges permitting the securing of the latching unit in place within the channel member by means of spot welding 88, 60 as clearly shown in Figure 3.

Attention is particularly directed to the fact that the elongated latching element, supported and interconnected with the supporting frame and the channel member, as shown in Figures 2 70 to 6, is rigidly fastened to the door assembly and cannot be removed therefrom. At the same time, however, the upwardly extending arms thereof and the intermediate rectangular conformations are free to move resiliently about the axes of the 75 arms against the resilient torsional resistance

thereof. That is to say, the upper and lower ends of the arms 68 are firmly fixed against rotation about the axes of the arms, whereas the intermediate portions are free from such attachment. As a result, the rectangular or latching portions, while normally urged together, as shown in Figures 2, 5, 6, and 7, may be resiliently separated against the spring tension of the vertically extending arms 68.

It will be apparent from the foregoing that, when the door is swung toward closed position, the forwardly projecting end of the keeper will progress relatively through the apertures 64, 66, and 80 to contact the inwardly extending portions of the keeper, which are, namely, the latches or arms (see Figure 6). These will be resiliently separated to admit the ends of the keeper and will spring to the position shown behind the edges of the cap member 26 when the door has reached closed position (Figure 5). This action takes place for the reason that, with the channel 38 in its normal, lowermost position, the latching portions 72 of the latching members are in substantial alinement with the respective keepers. When it is desired to release the latching engagement of the parts, the handle assembly is grasped to shift the inner handle 50 relatively upwardly, thus carrying upwardly the channel 38 and its associated latching mechanism. In so moving the keeper, engaging portions of the latching mechanism move upwardly to the position shown in Figure 4 where they are above and beyond the interengaging shoulders on the keeper. Obviously at this time parts are disengaged and the door may be freely opened.

Upon releasing the lower handle 50 the channel and associated mechanism falls into its original position for re-engagement with the keeper.

Attention is particularly directed to the fact that the present construction provides a latching structure which is characterized by a strutting action. That is to say, when it is attempted to open the door without releasing the latch, the engagement of the cap portion of the keeper, with the latches or arms 72 of the latch, tends to urge the opposed latches even closer together and results in the transmitting of a compressive force through the laterally extending arms 70 of the keeper members. Thus the relatively simple keeper structure is enabled to exert a surprisingly great force in resistance to unauthorized opening of the door and at the same time such opening forces tend to result in an even more secure

engagement of the latching parts. The compressive forces are in turn resisted by the re-entrant portions of the latch supporting member, which re-entrant portions are formed by the junction of the flange 82 with the main wall portion, which provide a recess for the vertically extending spring arms 68.

The present invention provides a simplified, compact keeper device which nevertheless is positive in operation. Unauthorized manipulation of the latches is prevented by virtue of the fact that the latch members present little or no surface susceptible to engagement by instruments, and further since the latches act on opposite sides of the keeper, whereby the release of one still results in interlocking of the other opposed latch member.

Changes may be made in the form, construction, and arrangement of the parts without departing from the spirit of the invention or sacrificing any of its advantages, and the right is hereby reserved to make all such changes as fairly fall within the scope of the following claim.

Having thus described my invention, what I claim as new and desire to secure by Letters Patent is:

A keeper for a latching means for a locker or the like, said keeper comprising a plate having a free edge portion, and a cap substantially coextensive with the free edge portion of the keeper plate, said cap being substantially U-shaped in cross section, the depth of the keeper being many times the depth of the cap, whereby such cap envelops substantially only the tip of the keeper, the outer free edges of the ends of the leg portions of the U-shaped cap providing relatively sharp shoulders extending perpendicularly from the opposed outer faces of the keeper plate to provide relatively abrupt latching abutments adapted to be engaged by opposed latches, the width of the shoulders taken from the planes of the outer faces of the keeper plate to the outer faces of the cap at the shoulder being sufficiently great compared to the width of the opposed latches whereby said shoulders engage and hold said latches from detachment from said keeper and the outer surface of the cap opposite said free edges of the cap being rounded to permit the latches to move over said cap from said rounded surface toward the opposite free edges and into engagement with the abutments formed by said sharp shoulders.

JOHN B. O'CONNOR.
